UNITED STATES PATENT OFFICE.

HENRY C. RUSSELL, OF TORONTO, ONTARIO, CANADA.

STEP-LADDER.

SPECIFICATION forming part of Letters Patent No. 357,233, dated February 8, 1887.

Application filed September 2, 1886. Serial No. 212,501. (No model.)

To all whom it may concern:

Be it known that I, HENRY CRANMER RUSSELL, of the city of Toronto, in the county of York, in the Province of Ontario, Canada, 5 manufacturer, have invented certain new and useful Improvements in Step-Ladders, of which the following is a specification.

The object of the invention is to design a step-ladder which may be folded up into a small 10 space and yet be strong and stiff when set for use; and it consists, essentially, in pivoting the steps to their vertical supports and providing a series of hinged or pivoted braces which, when set, will hold the ladder in a very stiff 15 and substantial manner, substantially as hereinafter more particularly explained.

Figure 1 is a perspective view of my improved step-ladder set ready for use. Fig. 2 exhibits the ladder as it will appear when 20 folded for transportation. Fig. 3 is a perspective back view showing the ladder in the act of being folded up. Fig. 4 is a perspective enlarged detail of the top step of the ladder, showing the manner of locking it.

25 A represents the steps, which are pivoted at *a* to the uprights or vertical supports B. The back legs or supports, C, are pivoted at *b* to the uprights B, immediately below the top step, A, against which their ends butt, so as 30 to prevent them opening up farther than the required distance.

D are foot-braces pivoted at *b*, one on each of the uprights B.

35 Notches *e* are made in the bottom step, A, into which the ends of the braces D fit when the ladder is set for use, as shown in Fig. 1, the said braces being held in position by the hooks E.

The back legs, C, are braced by the cross- 40 braces F, the upper ends of which are pivoted to the legs C at *f*. Notches are made in the other, ends of the braces F, so that they may be slipped over the pins *g*, as indicated.

G is a foot-brace pivoted to the legs C, as 45 indicated.

H is a bar hinged to the top step, A, and fitting between the uprights B.

When the ladder is set for use, as shown in Fig. 1, the bar H is set down in position by the pivoted plates I, which, when locked into 50 the uprights B, as indicated in the drawings, hold the bar H stiffly in position, and thereby lock the back legs, C, and prevent them from folding in.

When it is desired to fold the ladder, the 55 pivoted plates I are disengaged from the uprights B, when the bar H may be folded back onto the top step, A. The cross-braces F are lifted off their respective pins G and folded straight with the particular leg on which they 60 are pivoted, notches *i* being made so as to permit them to slip over the pin G. The foot-braces D are removed from their respective notches, when by bringing the legs C toward the upright B, as indicated in Fig. 3, the whole 65 ladder may be folded up into the position indicated in Fig. 2.

What I claim as my invention is—

1. A step-ladder in which the steps A are pivoted at *a* upon the uprights B and the back 70 legs, C, pivoted at *b* to the said uprights B, in combination with the bar H, hinged upon the top step, A, and provided with pivoted plates I, substantially as and for the purpose specified.

2. A step ladder in which the steps A are pivoted at *a* upon the uprights B and the back 75 legs, C, pivoted at *b* to the said uprights B, in combination with the bar H, hinged upon the top step, A, and foot-braces D, pivoted near 80 the bottom of the uprights B, substantially as and for the purpose specified.

3. A step-ladder in which the steps A are pivoted at *a* upon the uprights B and the back 85 legs, C, pivoted at *b* to the said uprights B, in combination with the cross-braces F and pivoted foot-brace G, substantially as and for the purpose specified.

Toronto, August 27, 1886.

H. C. RUSSELL.

In presence of—

CHARLES C. BALDWIN,
CHARLES H. RICHES.
